HARRY L. EVANS AND GEORGE I. HOHL, OF NEWPORT, RHODE ISLAND, ASSIGNEES TO
CARTONING MACHINERY CORPORATION, OF NEWPORT, RHODE ISLAND, A CORPORA-
TION OF NEW JERSEY

WRAPPING MACHINE

Application filed February 8, 1930. Serial No. 426,809.

This invention relates to automatic wrapping machines; and the invention has reference, more particularly, to machines for wrapping articles or materials in cellophane paper.

Cellophane paper, because of its clear transparent character and comparative toughness, is a very desirable wrapping material, and has now been extensively used in hand wrapping. Its transparency makes possible the full display of articles or materials enclosed therein in such manner that the color and other physical characteristics of the enclosed articles or materials are in no way concealed or undesirably modified in appearance. Owing to the fact, however, that cellophane paper is very sensitive to temperature and humidity changes, the same is subject to a considerable degree of expansion and contraction, and consequently difficulty has been experienced in handling the same by automatic machine wrapping means and methods. For example, if the machine produced wrapping thereof is too tight or close fitting relative to the articles or materials enclosed therein, and shrinkage occurs, the wrapping is likely to split, break open sealed or glued folds, or be otherwise disrupted; and, on the other hand, if the wrapping thereof is too loose, and expansion occurs, the wrapping is likely to buckle and wrinkle to the detriment of the appearance of the wrapped articles or materials.

This invention, therefore, has for its principal object to provide an automatic wrapping machine especially adapted to manipulate cellophane paper in the production of enclosing wrappers about articles and materials of various kinds; and to this end the machine includes means adapted to feed such cellophane paper from a supply thereof, and means to fold the same about the articles or materials to be wrapped therein, all in such manner as to obtain a good appearance and neat fitting of the cellophane paper wrapper about the articles or materials enclosed thereby, while at the same time leaving sufficient looseness, particularly at the points where end folds are glued together or sealed, that contraction and expansion of the cellophane

paper will not split, break open sealed or glued folds, or otherwise disrupt or detrimentally affect either the integrity or appearance of the wrapper.

Another object of this invention is to provide a relatively simple, efficient and speedy machine calculated to produce desired wrappings in a rapid and uniform manner; and, furthermore, this invention provides a novel means for making sealed wrapper end folds.

Another object is to provide means co-operative with the wrapping devices for first applying to the articles or materials to be wrapped in cellophane paper, a label band, so that the same will be enclosed by the subsequently applied cellophane wrapper, through which it will be plainly visible, while yet protected by the wrapper against soiling or mutilation.

Other objects of this invention, not at this time more particularly enumerated, will be understood from the following detailed description of the same.

An illustrative embodiment of this invention is shown in the accompanying drawings, in which:—

Figs. 1 and 1^A, taken together, show a side elevation of a wrapping machine made according to this invention; Fig. 2 is a top plan view of that portion of the machine shown in Fig. 1^A, with certain parts in section; and Fig. 3 is a longitudinal section of parts of the machine, to illustrate the means for propelling the articles or materials and wrappers therefor relative to the wrapper folding mechanisms.

Figs. 4 to 7 inclusive are fragmentary diagrammatic sectional views taken on line 4—4 in Fig. 2, and respectively illustrating various stages in the operation of the end fold tucking rolls of the mechanism.

Figs. 8 to 11 inclusive are fragmentary diagrammatic sectional views, respectively taken on lines 8—8, 9—9, 10—10 and 11—11 in Fig. 2, to illustrate various steps in the formation and positioning the end folds of the wrapper preparatory to applying a sealing adhesive thereto.

Fig. 12 is a fragmentary diagrammatic sectional view, taken on line 12—12 in Fig. 2.

to illustrate the operation of applying adhesive to the end folds of the wrapper.

Fig. 13 is a fragmentary diagrammatic sectional view, taken on line 13—13 in Fig. 2 to illustrate the means for upturning the end folds of the wrapper.

Fig. 14 is a fragmentary sectional view, taken on line 14—14 in Fig. 2, to illustrate the means for infolding and laying the wrapper end folds in sealed relation to the main body of the wrapper.

Figs. 15 and 16 are enlarged fragmentary sectional views to illustrate the operations of the end-fold manipulating and laying devices.

Similar characters of reference are employed in the above described views, to indicate corresponding parts.

To illustrate the construction and operation of the wrapping machine of this invention, the same is shown as designed to wrap flat rectangular articles, such e. g. as cards of tape, binding or the like. The tape or binding is wound about a rectangular cardboard core. In handling such class of work it is desirable to first dispose about the same a printed label band, thereupon applying over and about the label band and card of tape an enclosing wrapper of cellophane paper.

Referring to the drawings, the reference character 20 indicates a bed-plate upon which wrapping mechanism is mounted. This bed-plate, in practice is usually supported on suitable standards or leg frames (not shown).

Journalized in a pedestal bearing 21, which is supported on said bed-plate 20, is the shaft 22 of a carrier head 23. Said carrier-head 23 is driven by any suitable power transmission means (not shown) which is adapted to produce intermittent rotation thereof in the direction of the arrow α in Fig. 1. Said carrier head 23 is provided, in radial extension therefrom, with a plurality of receiving pockets 24, each formed by parallel wall portions, one of which is provided with a spring cushioned yieldable face plate 25.

Arranged at the forward side of said carrier head 23 in horizontal plane, and extending toward the same in alignment with an opposed receiving pocket 24 thereof as the latter is disposed during the periods of rest of said carrier head, is a feed table 26. Cooperative with said feed table 26 is a movable conveyer 27, preferably of the endless chain type, and having spaced apart push fingers 28 to engage the articles to be wrapped so as to move the same along said feed table 26 successively toward the carrier head 23. Bearing standards 29 are fixed on said bed-plate in which is journalized a shaft 30 carrying the sprockets 31 of the chain conveyer 27.

Positioned in advance of the carrier head 23 is a label band supply holder and feeding

means, the latter being adapted to deliver a label band intermediate a carrier head receiving pocket 24 and an article about to be entered therein, in carrying out the operations of applying said label band to said article.

The label band supply holder comprises a magazine 32 supported by a suitable framework 33 connected with the upper ends of said bearing standards 29, and adapted to hold a stack or pile of label bands. The magazine 32 possesses a bottom plate 34, and further includes, at the bottom of its rearward end portion, one or more brackets 35 to which are affixed upwardly and rearwardly inclined and directed retaining spurs 36, preferably in the form of sharp needle-like points. Intermediate the spurs 36 and plate 34, the bottom of the magazine is open. Journalized for disposition beneath this opening at the bottom of the magazine is a feed roller 37, provided along a portion of its periphery with a circumferentially off-set frictional gripping section 38, preferably made of soft rubber or other frictional material, the same being adapted, at properly timed moments during rotation of said roller, to engage a bottom-most label band and feed the same forwardly and outwardly from the magazine. Aligned with and extending from the bottom plate 34, is a downwardly curved guideway 39, adapted to lead the discharged label band downwardly between a series of gripping and feeding rollers 40, whereby the label band is vertically suspended between a carrier head pocket 24 and an article to be entered therein. The gripping and feeding rollers 40 are driven by gearing 41 from the feed roller 37, said gearing including a segmental gear 42, whereby timed intermittent actuation of the gripping and feeding rollers 40 is attained.

Aligned beneath the depending end of the guideway 39 is means to apply adhesive to an end of a delivered label band prior to its entrance with the article, to which it is to be applied, into the carrier head pocket 24. This means comprises a vertical backing plate 43 with cooperating guides 44 to position the lower end of the label band against said backing plate. Adjacent to said backing plate 43 is a glue-pot 45 in which runs a glue-pick-up roller 46. Arranged to rotate intermediate said pick-up roller 46 and backing plate 43 is dauber arm 47, which, in its rotation, contacts with the glue carried on the surface of said pick-up roller, and then contacts with the depending end of the label band so as to apply a desired quantity of glue thereto. Said dauber arm 47 may be driven, in timed relation to the delivery of the label bands to the backing plate 43, by any suitable transmission means (not shown).

Means are provided for inserting an article and label band into the pockets of the carrier head 23 at one side thereof and eject-

ing the same from the other side thereof, operative while the carrier head is at rest. This means comprises longitudinally reciprocable plates 48 having slots 49 and 50 to movably support the same on anti-friction rollers 51 and 52, which are respectively mounted on the shafts 22 and 30. Journaled in and extending between said reciprocable plates 48 is a transverse shaft 53, to which are fixed delivery fingers 54 adapted to engage the end portions of the article, which end portions project respectively beyond opposite sides of the feed table 26 and beyond opposite sides of the carrier head 23. Also fixed on said shaft 53 is a lever arm 55, having a laterally projecting stud 56. Mounted in a guide standard 57 is a vertically reciprocable member 58 provided at its upper end with a longitudinally slotted head 59, within the slot 60 of which is engaged the stud 56 of said lever arm 55. When said member 58 is raised to its upward limit of movement (as shown in Fig. 1), the lever arm 55 will be up-swung to turn the shaft 53 so as to swing down the delivery fingers 54 into article engaging position. The feed conveyer 27 having delivered an article in position adjacent to a pocket 24 of the carrier head 23, the member 58 is timed to rise, thereupon swinging downward the delivery fingers 54 behind said article. While the parts are in this position, a suitable timed transmission means (not shown) operates to cause a forward movement of said reciprocable plates 48, thus causing said delivery fingers 54 to engage the article and push the same forwardly and into the waiting pocket 24 of the carrier head 23. As the article is thus moved into the pocket 24, the same engages the delivered label band so that the latter is doubled about the article as entered in said pocket, with a glue carrying end of the label band projecting from the circumference of the carrier head.

After an article and label band has been entered in the carrier head 23, the latter by intermittent rotation in the direction of the arrow α in Fig. 1, carries the article and label band into alignment with a stationary folder means (to be subsequently described) which is located at the opposite side of said carrier head. During the rotative movement of said carrier head 23, the delivery fingers 54 are raised and retracted to normal initial position. This is accomplished by the lowering of the slotted head 59 by downward retraction of the vertically reciprocable member 58 prior to the retractive stroke of the reciprocable plates 48. This lowering of said slotted head 59 serves to swing down the lever arm 55 to turn the shaft 53 so as to swing up the delivery fingers 54 out of the path of movement of said articles, so that on rearward retraction of the reciprocable plates 48 said fingers will pass over the succeeding article which is moved forward by the con-

veyer 27 ready to be inserted with the next delivered label band into the succeeding pocket 24 of the carrier head 23. These operations being repeated in time with the step by step movements of said carrier head.

The means for ejecting an article and label band from the carrier-head 23 is also carried by the reciprocable plates 48, and comprises ejector fingers 61 pivotally connected with the latter, the same being lowered to article engaging position and raised out of the path of movement of the articles by lever arms 62 which are interconnected by links 63 with lever arms 64 fixed to said shaft 53, whereby said ejector fingers 61 operate in time with said delivery fingers 54 while the carrier head 23 is at rest.

The stationary folder means above mentioned comprises a pair of vertically spaced folder plates 65 and 66, suitably fixed and supported by a standard or supporting post 67, so as to be aligned with a rest position of the pockets 24 of the carrier head 23. While an article and label band are being delivered into a carrier-head pocket 24 at one side of the carrier head, an article and label band are ejected by the ejector fingers 61 from the opposite side of the carrier head 23, and delivered between the folder plates 65—66. As the article and label band enters between said folder plates 65—66, the projecting glue bearing end of the label band will be engaged and turned over upon the article, so as to complete the folding of the label band about the latter, and so as to press said glue bearing end into adhering engagement with the first folded end of the label band.

Journaled in a pedestal bearing 68', which is mounted on said bed-plate 20, is the shaft 68 of a second carrier head 69. Said carrier head 69 is driven by any suitable power transmission means (not shown), which is adapted to produce intermittent rotation thereof in the direction of the arrow γ in Fig. 1, and in time with the movements of the carrier head 23. Said carrier head 69 is also provided, in radial extension therefrom, with a plurality of receiving pockets 70, each formed by parallel wall portions, one of which is provided with a spring cushioned yieldable face plate 71.

Cooperative with said carrier head 69 is means for feeding cellophane paper to form wrappers for the articles operated on. This paper feed means comprises a supporting frame-work 72 carried by extensions of the pedestal bearings 21 and 67. Said frame-work 72 includes an up-standing post 73 upon which is fixed a spindle 74 for rotatably mounting a roll of cellophane paper 75. Rotatably supported by said frame-work 72 are a pair of opposed paper feed rolls 76 and 77, the latter being spring pressed toward the former so as to grip the paper therebetween. Means are provided for causing timed rota-

tion of said feed rolls 76-77, whereby the paper is drawn down off the supply roll. This means comprises a stud shaft 78 on which is rotatably mounted a drive gear 79 which meshes with a gear 80 on the shaft of the feed roll 76 so as to drive the latter. Said feed rolls 76 and 77 are geared together for operative rotation, respectively in opposite directions, by gears 81 and 82. Pivoted 10 mounted on the stud shaft 78 is an oscillatable arm 83 having pawls 84-85 to engage a ratchet wheel 86 which drives the drive gear 79. Properly timed oscillation of the arm 83 is produced by means of a suitably driven cam 87 which operatively engages the roller stud 88 carried by a pivoted lever arm 89, the free end of which is connected with said oscillatable arm 83 by a link 90.

Cooperating with and forming a part of 20 the paper feed mechanism is a vertically reciprocable paper gripping means which engages with the side margins at the free end of paper strip as the same is fed downward by the feed rolls 76-77, so as to hold the 25 cellophane paper smoothly spread in front of a pocket 70 of the carrier head 69, and free from curls or wrinkles, ready to be engaged by and entered with an article into said pocket. Such means is essential for assurance of proper delivery and disposition 30 of the cellophane paper, for the reason that the latter has a strong tendency to curl, especially in humid or damp weather. This paper gripping means comprises vertically 35 reciprocable members 91 at each side of the path of paper movement, the reciprocations of which may be produced by any suitable form of actuating means (not shown) adapted to cause timed cooperation with the paper 40 feed rolls and article delivery means functioning to deliver the articles with the paper into the pockets of the carrier head 69. Connected with each member 91 is a fixed gripping jaw 92 and pivoted gripping jaw 93, 45 the latter being biased to open or separated relation to the former. Journaled in each member 91 is rock-shaft 94 having on its inwardly projecting end an eccentric cam 95, adapted at proper times to thrust said 50 pivoted gripping jaw 93 into paper gripping relation to said fixed jaw 92. Fixed on the outer end of said rock-shaft 94 is a lever arm 96, having, adjacent to its free end, a lateral stud 97. Secured to said supporting post 67 55 is a stop-lug 98, which engages and up-turns said lever arm 96 to in turn move the cam 95 to jaw opening or releasing position, when the members 91 reach the limit of their downward movement. Pivoted on the outer side 60 of each member 91 is a trigger-finger 99, one end of which bears on the stud 97 of the lever arm 96. Provided at the opposite end of said trigger-finger 99 is a chamfered nosing 100. Fixed on the upper end of said 65 supporting post 67 is a bracket extension 101

which carries a spring biased yieldable stop-dog 102, the same being disposed in the path of movement of the nosing 100 of said trigger-finger 99.

Cooperating with the paper feed mechanism is a severing means adapted to sever from the downwardly fed length of paper a portion thereof sufficient to provide a wrapper sheet. This severing means comprises a stationary shear blade 103 secured to the frame-work 72 and disposed beneath the feed rolls 76-77. Pivoted connected with said stationary shear blade 103 is a movable shear blade 104. The means for producing properly timed operation of said movable shear blade 104 comprises a cam 105 which serves to oscillate a lever 106, the latter having a roller stud 107 to engage in the race of said cam 105. Slidably mounted in connection with the frame-work 72 is reciprocable slide-piece 108, the rearward end of which is connected with the free end of said lever 106 by a link 109. The forward end of said slide-piece 108 is pivotally connected to the free end of said movable shear blade 104. 90

In the operation of the machine, prior to the delivery of an article to be wrapped into a pocket 70 of the carrier head 69, the paper feed mechanism is timed to function in the following manner. Through the described 95 actuating mechanism, the feed rolls 76-77 are rotated so as to draw the cellophane paper off the supply roll and feed the same downward through the open severing means and in front of the carrier head 69. As the feed rolls 76-77 start the paper downward, the actuating means serving the gripping devices moves the members 91 upward toward the free end of the downwardly fed paper. As the members 91 rise, the nosings 100 of the trigger-fingers 99 are carried upwardly past the yieldable stop-dogs 102, the latter yielding to this movement thereof. The gripping jaws 92 and 93 being in open relation, will receive the end of the paper there- 100 between as it passes the shear blades, whereupon the actuating means serving the gripping devices will reverse the movement of the members 91, causing the same to move downward in time with the continued downward feeding of the paper by the feed rolls 76-77. As this downward movement is initiated, the nosings 100 of the trigger-fingers 99 are carried downwardly into operative engagement with the stop-dogs 102, whereby 105 the trigger-fingers are swung downward, to in turn engage and swing downward the lever arms 96 so as to turn the cams 95 into closing relation to the pivoted gripping jaws 93, the latter thereupon cooperating with the fixed gripping jaws 92 to grip the lower corners of the paper. The paper is thus held in its downward movement, against curling and against obstructed engagement 110 with parts of the mechanism past which it is 115 120 125 130

5 moved, while at the same time the paper is held smoothly spread across the forward side of the carrier head 69 so as to be engaged by an article and entered therewith in a pocket 70 of the latter. As the limit of downward feeding movement of the paper is approached, the lever arms 96 engage the fixed stop-lugs 98, which, as the downward movement of the members 91 is completed, 10 serve to turn upwardly the lever arms 96 to release the cams 95, and thus permit opening movement of the movable gripping jaws 93, while at the same time re-setting the trigger-fingers 99 to normal initial positions. 15 As this occurs the severing means is timed to operate whereby a down-drawn length of paper is severed from the supply, ready to form a wrapper. Substantially simultaneously with the release of the gripping jaws 92-93 and the severing of the paper, the 20 means for delivering the waiting article into an opposed pocket 70 of the carrier head 69 functions so as to immediately engage the paper and partially fold the same about the 25 article during its movement into said pocket. The article delivery means comprises a second set of delivery fingers 110 pivotally connected with the forward ends of the reciprocable plates 48, the same being so arranged 30 as to be raised to article engaging position and lowered out of the path of movement of the articles by lever arms 111 connected by links 112 to lever extensions 113 forming a part of said lever arms 62, all whereby said 35 delivery fingers 110 operate in time with the operations of the heretofore described delivery fingers 54 and ejector fingers 61, as will be understood from an inspection of Fig. 1 of the drawings. 40 When an article and wrapper is entered in a pocket of the carrier head 69, the latter is intermittently rotated in the direction of the arrow *y* in Fig. 1 to carry the same around to folder devices into which the same is to 45 be delivered from the carrier head. Located at a stage in the intermittent rotation of the carrier head, in advance of the position of the folder devices into which the article and wrapper is to be delivered when discharged 50 from the carrier head 69, is means for applying adhesive to the wrapper portion which projects from the pocket of the carrier head. This means comprises a supporting platform 114 carried by extensions 115 of the frame-work 72. Mounted on said platform 114 is a 55 glue reservoir 116, in which is arranged a rotatable glue pick-up roller 117. Formed in connection with the end of said glue reservoir, which is adjacent to the carrier head 60 69, is a wrapper backing or supporting shelf 118. Means are provided for engaging and laying back the projecting portion of the wrapper upon the backing or supporting shelf 118 during a period of rest of the carrier head, whereby glue may be applied to 65 such portion of the wrapper. This latter means comprises rotatable spreader members 119 adjacent to each side of the carrier head, and adapted, when rotated, to engage the side margins of the projecting portion of the 70 wrapper so as to turn or bend the latter portion forwardly and down upon the backing or supporting shelf 118. Said rotatable spreader members 119 are fixed on the lower ends of spindles 120 journaled in bearing brackets 121 mounted on the frame-work 72. A transverse drive shaft 122 is journaled in said frame-work 72, and is adapted to be driven in properly timed relation to the movements of the carrier head 69 by any suitable 75 transmission means (not shown). Said spindles 120 are driven from said shaft 122 by intermeshing bevel gears 123-124, as shown in Fig. 1. The glue pick-up roller 117 is driven from said shaft 122 by a chain and 80 sprocket transmission 125, or in any other suitable manner. Connected with said glue-reservoir 116 are bearing arms 126 which project over said backing or supporting shelf 118. Journaled in and between said bearing arms 126 is a shaft 127 on which is fixed a dauber arm 128; the shaft 127 being driven from said pick-up roller 117 by intermediate 85 gearing 129. The rotation of the dauber arm 128 is timed to engage the surface of said pick-up roller 117 to receive an application of glue therefrom, and then in its travel to contact with the wrapper portion, which has been previously spread on said backing or 90 supporting shelf 118 in the manner above described, so as to transfer and apply thereto an application of said glue. 95 Opposed to the carrier head 69 so as to extend forwardly and away therefrom, and aligned with the pockets 70, when the latter are disposed in position at which articles and their wrappers are discharged therefrom, is a suitably runway 130, the same having longitudinal slots 131 therein, to accommodate the movements of article propelling means adapted to propel the articles step by step along said runway and in operative relation to various wrapper fold forming devices which border said runway. 100 105 110 115 120 125 130

The article propelling means comprises propeller bars 132 having up-standing push-fingers 133 spaced longitudinally apart from end to end thereof. Said propeller bars 132 are actuated in a longitudinally and vertically reciprocable path of movement indicated by the diagram *z* in Fig. 3. To this end said propeller bars are slidably carried on guide blocks 134 which are fixed on vertically reciprocable bars 135 movable in guide brackets 136. Pivotally connected with said guide brackets are bell-crank levers 137, one arm each of the bell-crank levers are respectively connected with the vertically reciprocable bars 135, and the other arms thereof are interconnected by a link 138, so that the bell-

crank levers work together. The means for actuating the bell-crank levers to cause timed rise and fall of the propeller bars 132, to carry the same into and out of the path of movement of the articles and their wrappers, 5 as moved along said runway 130, comprises a suitably driven rotatable cam 139 and a reciprocable cross-head 140 having a roller stud 141 operatively engaged in the race of said cam 139. Movable with one of said bell-crank levers 137 is a lever arm 142, which is connected with one end of the cross-head 140 by a connecting rod 143. The opposite end of the cross-head 140 is coupled 10 through connecting rod 144 with a lever arm 145 adapted to oscillate lever members 146 serving to produce timed vertical reciprocation of the member 58 previously described. The longitudinal reciprocation of said propeller bars 132 is caused by suitably actuated 15 oscillatable levers 147, the upper ends of which are operatively coupled with said propeller bars by links 148.

Positioned at the inner end of the runway 25 130, which is opposed to a pocket 70 of the carrier-head 69 brought to rest in alignment with said runway, and spaced above said runway, is a folder plate 149, supported by rods 150 depending from said platform 114. 30 The under side of said folder plate 149 is provided with a spring cushioned presser plate 151. Secured to the inner margin of said folder plate 149 is a folder lip 152.

As the carrier head 69 rotates to carry an 35 article and wrapper from the glue application station to the point of discharge to the folder devices, the projecting portion of the wrapper will engage and be up-turned by the folder lip 152, so that as the carrier head 69 comes 40 to rest the article and wrapper is disposed so that, when discharged from the carrier-head pocket 70 upon the runway 130 and beneath the folder plate 149, the up-turned projecting portion of the wrapper will be turned down- 45 ward and rearwardly over the other folded end of the wrapper, and the glue application applied to the former will cause the same to 50 adhere to the latter, thus completing the longitudinal folding of the wrapper about the 55 article. The discharge of the article and its wrapper from the carrier-head 69 to the runway and beneath the folder plate 149, is effected by a forward movement of the propeller bars 132, the readward push-fingers 133 60 of which have been carried beneath and then up behind the end portions of the article when the propeller bars were retracted. At the end of the forward stroke of the propeller bars 132, the article comes to rest in 65 position to be engaged by end fold tucking means mounted at the sides of the runway 130, which means is timed to be operative while the propeller bars 132 are being retracted for a succeeding article propelling stroke.

Said end fold tucking means comprises rotatable tucking rolls. Each said tucking roll is journaled in bearings 153 mounted on base-plate structures 154, which are in turn supported on standards 155 rising from 70 the bed-plate 20 and an extension 20' thereof. Journaled in and extending longitudinally between standards 155, at one side of the machine, is a drive shaft 156, which is driven by suitable transmission means from 75 the power source of the machine. In like manner there is journaled in and extending longitudinally between standards 155, at the other side of the machine, a corresponding shaft 157, driven from said shaft 156 by chain 80 and sprocket transmission 158 (see Fig. 14). Journaled in bearings 159 fixed on the base-plate structure 154, at each side of the machine, are counter shafts 160, which are respectively driven from the respective shafts 85 156 and 157, either by chain and sprocket transmission 161 (as shown in Fig. 2 at one side of the machine), or by gearing 162 (as shown in Fig. 2 at the other side of the machine). Said tucking rolls are driven from 90 counter shafts 160 through intermediate gearing 163.

Each tucking roll 164 is provided in its circumferential face with a sector-shaped open portion 165 bounded on its leading side, 95 throughout the length of the roll, by a radial face 166 slightly chamfered endwise toward the carrier head 69. The tucking rolls are so positioned that their longitudinal axes are substantially in the plane of the article supporting surface of the runway 130, to which the rolls are opposed. As the articles, with wrappers folded and secured longitudinally about the same, are brought to their point of rest in alignment with the tucking rolls, the latter will be positioned so that the projecting end portions of the wrapper will ride over the radial faces 166, and will thus extend into the open portions 165 of said rolls. Each tucking roll is provided on the trailing side of its open portion 165 with a tucker member 167, of a width approximating the width of the article. Said tucker member 167 is provided in its end faces with V-shaped marginal grooves 168 concentric to the axis 100 of the roll and extending the entire depth of the tucker member. Rearward of the tucker member, the roll is of full length, and formed in the part thereof adjacent to said tucker member are inwardly directed oblique tuck 105 turning grooves 169, respectively leading from the marginal grooves 168 of the tucker member, and gradually reducing in depth outwardly until merging with the circumferential surface of the main body of the roll. The 110 body of the roll beyond the radial face 166 is cut back circumferentially for a short distance to provide a clearance space 170.

While an article and its wrapper is at rest 115 on the runway 130, and the ends of the wrap-

pers entered in the open portions 165 of the tucking rolls (as shown in Fig. 4), rotation of the rolls will operate to tuck and laterally fold the projecting end portions of the wrapper to provide the latter with end closing flaps. The operation of the tucking rolls is illustrated in Figs. 4 to 7 inclusive of the drawings. By its rotation the tucker member 167 of a roll is carried toward the projecting wrapper end, so as to engage the upper ply of the wrapper, whereby the same is folded down over the end of the article, and at the same time into coextensive contact with the under ply, thus also forming up-standing tuck folds at the sides of the thus formed closing flap (see Fig. 5). Continued rotation of the roll turns down the closing flap over the margin of an extension 171 of helically slotted guide plate 172, which is mounted contiguous to the inner edge of runway plate 130. As the closing flap is thus turned down, the up-standing tuck-folds tend to swing inward thereover, clearance for such movement thereof being provided by the grooves 168 in the sides of said tucker member 167, so that as the roll continues to turn these tuck-folds will be led into the tuck turning grooves 169, which compel the tuck-folds to fold down and inwardly over the closing flap (see Fig. 6). On further rotation of the roll its smooth circumferential surface is moved against the in-turned tuck-folds so as to crease and iron the same down in desired position (see Fig. 7).

By the time the clearance space 170 of the roll is brought in opposition to the down turned and folded closing flap, the propeller bars 132, which in the meantime have been dropped below the runway 130 and retracted ready for another article propelling stroke, are again raised to engage certain of their push fingers 133 behind the article, and, when thus positioned, move forward to push the article and wrapper forwardly along the runway 130 to the next point of rest. As the article and wrapper is so moved, the down turned closing flap, at each end of the article, is moved through a helical slot 173 of the guide plate 172, whereby the closing flap is turned upwardly to horizontal position, so that the same comes to rest over a resilient or spring cushioned backing plate 174 adapted to support the closing flap for application of adhesive thereto. In order to retain the wrapper in-folded against the article, at the point thereof from which the closing flap springs, a thin vertical keeper plate 175 is fixed in place, with its lower margin spaced from the level of the runway 130 a sufficient distance to permit the closing flap to move thereunder. The above described operations will be best understood from an inspection of Figs. 8 to 11 inclusive of the drawings.

Located on each side of the runway 130, at points aligned with a point of rest of the

articles and wrappers beyond the tucking rolls, are means for applying adhesive or glue to the closing flaps prior to the operations of folding the latter inwardly and over the body of the wrapper. Each such means comprises a glue reservoir 176 having a rotatable pick-up roller 177, the same being driven by suitable clutch mechanism from an adjacent counter-shaft 160. Mounted in bearings 178 is a rock-shaft 179 on which is fixed an oscillatable dauber arm 180. At proper moments, through suitable transmission means, the dauber arm 180 is swung back to engage the pick-up roller 177 to take up therefrom an application of glue, thereupon being swung forward to engage a closing flap of wrapper to transfer the glue application thereto (see Fig. 12). The yieldable backing plates 174 so support the closing flaps as to assure equal depositing pressure of the dauber arms relative thereto.

By succeeding operations of the propeller bars 132, the article and wrapper is carried further along the runway 130, so as to engage in passing up-turning blocks 181, having upwardly and forwardly inclined top surfaces, and perpendicular inner side faces, each having at its foot a curved bottom marginal element 182. As the closing flaps engage the blocks 181 the same will be turned upwardly across the ends of the article, as shown in Fig. 13. The rounded or curved element 182 allows the juncture of the closing flap and main body of the wrapper to assume a somewhat outwardly curved and not too tightly creased fold, whereby a little looseness of the wrapper at such points is provided for, so that it will readily compensate itself under stresses of contraction and expansion.

By further succeeding operations of the propeller bars 132, the article and wrapper, with the closing flaps up-turned, as described, is conveyed to and brought to rest in alignment with fold turning devices which border the sides of the runway 130. These fold turning devices each comprise a swingable shutter 183 pivotally supported by fulcrum blocks 184. This shutter 183, when actuated, is adapted to swing down from vertical position to horizontal position overlapping an end of the article, thereby turning over the up-standing closing flap of the wrapper downwardly upon the body of the wrapper, the glue bearing face of the closing flap being thereby pressed into adhering relation to the body of the wrapper so as to complete the folding and securing of the latter about the article and its encircling label band. The means for producing properly timed oscillation of the shutter 183 comprises pivoted levers 185, having open yoke portions 186 in which are operatively engaged rotatable cams 187 respectively driven by the shafts 156 and 157. The upper ends of

said levers 185 are operatively connected with said shutters 183 by links 188.

5 Cooperative with said shutters 183 are vertically movable spring cushioned shaping members 189 having curved lips 190 to overhang the ends of the articles and their wrappers. These shaping members 189 lie underneath the shutters 183 so as to be depressed by the downward swinging movement 10 of the same, whereby the lips 190 are caused to engage and round over the fold of the closing flaps of the wrapper, as the former is over turned upon the body of the latter by the operation of the shutters 183; thus 15 further assuring a little looseness of the wrapper at such points so as to readily compensate for contraction and expansion thereof (see Figs. 15 and 16).

20 After the folding of the enveloping wrappers of the articles has been completed by the operation of the shutters 183 and shaping members 189, further operation of the propeller bars 132 will eject the completely wrapped articles from the machine.

25 In order to hold the articles and their wrappers against displacement, during their movement through the runway 130 and while subject to the operations of the wrapper end folding devices above described, a top plate 30 191 is provided to overlie the articles moving through the runway. This top plate is hingedly secured by carrier arms 192 to fulcrum posts 193, so that the same may be 35 swung open, when desired, to give access to the articles moving through the runway.

It will be obvious from the above description that the machine of the instant invention provides a means peculiarly adapted 40 for wrapping articles in cellophane paper; the wrapping operations being progressively carried out during the step by step movement of the articles through the machine in continuing succession, whereby a comparatively high speed automatic operation is attained with resultant large capacity of output 45 during a given period of time.

It will be understood that many changes could be made in the above described constructions and many apparently widely different embodiments of this invention could 50 be made without departing from the scope thereof as defined in the appended claims, consequently it is intended that all matter contained in the above description or shown 55 in the accompanying drawings, shall be interpreted as illustrative and not in a limiting sense.

Having thus described our invention, we claim:-

60 1. In a machine for the purposes described, an intermittently rotatable carrier head having radial pockets, means for feeding paper from a supply roll across the mouth of a pocket at one side of said carrier head, reciprocal means for gripping the free end

of the fed paper to hold the same smoothly spread while moved and until inserted in said pocket, means for severing the fed paper to form a wrapper, means for moving an article with such wrapper into said carrier head pocket to partially fold the wrapper about the article with a portion thereof projecting from said pocket, glue applying means adjacent to said carrier head, means to support said projecting wrapper portion subject to operation of said glue applying means, means operative to lay back said projecting wrapper portion upon said supporting means, means to eject partially wrapped articles from said carrier head, a runway to receive the ejected partially wrapped articles, a folder means at the receiving end of said runway adapted to fold the glue bearing portion of a wrapper to complete the longitudinal folding thereof about an article, means for moving the longitudinally wrapped articles through said runway, and means bordering said runway for producing and closing end folds of the wrappers.

2. In a machine for the purposes described, the combination with means for folding wrappers about an article of means for feeding paper, from a supply roll, intermediate an article to be wrapped and the wrapper folding means, reciprocal means for gripping the free end of the fed paper to hold the same smoothly spread while being moved into position and until delivered with the article to be wrapped to the wrapper folding means, means to sever the fed paper to form a wrapper, and means for delivering an article with the thus formed wrapper to the wrapper folding means.

3. In a machine for the purposes described, the combination with means for folding wrappers about an article of means for feeding paper, from a supply roll, intermediate an article to be wrapped and the wrapper folding means, means for holding the paper smoothly spread while being moved into position and until delivered with the article to be wrapped to the wrapper folding means, said holding means comprising reciprocal means having gripping jaws, means to actuate said gripping jaws, means in the path of movement of said reciprocal means operative to engage said actuating means to close said jaws in gripping relation to the paper during feeding movement thereof, and means also in the path of movement of said reciprocal means operative to engage said actuating means to open said jaws to release the paper when moved to position, means to sever the fed paper to form a wrapper, and means for delivering an article with the thus formed wrapper to the wrapper folding means.

4. In a machine for the purposes described, the combination with means for folding wrappers about an article of means for feeding paper, from a supply roll, intermediate

- an article to be wrapped and the wrapper feeding means, means for holding the paper smoothly spread while being moved into position and until delivered with the article to be wrapped to the wrapper folding means, said holding means comprising reciprocable means having a fixed gripping jaw and a cooperating movable gripping jaw normally biased to open position, a cam for actuating said movable gripping jaw, a lever controlling said cam, a pivoted trigger finger adapted to move said lever and cam to gripping jaw closing position, a trip means to actuate said trigger finger, and a fixed stop to engage said lever and move the same and said cam to gripping jaw releasing position. 5. In a machine for the purposes described, an intermittently rotatable carrier head having radial pockets to receive articles and wrappers therefor whereby the latter are partially longitudinally folded about the former so as to leave portions of the wrappers outwardly projecting from the pockets, glue applying means adjacent to said carrier head, means to support a projecting wrapper portion subject to operation of said glue applying means, means operative to lay back said projecting wrapper portion upon said supporting means for engagement by said glue applying means, and folder means to receive partially wrapped articles when ejected from the pockets of said carrier head whereby the glue bearing portions of the wrappers thereof are folded over to complete 35 the longitudinal folding of the wrappers about the articles. 6. In a machine for the purposes described, means for folding wrappers longitudinally about articles in combination with a runway to receive the longitudinally wrapped articles, means for moving the longitudinally wrapped articles through said runway, and means bordering said runway for producing and closing end folds of the wrappers, said latter means including rotatable tucking rolls having means to engage the ends of the wrappers to tuck and fold the same to form closing flaps, means to upturn said closing flaps across the ends of the articles, and oscillatable shutters to inwardly down-turn the raised closing flaps over the bodies of the wrappers to complete the wrapping operations. 7. In a machine for the purposes described, means for folding wrappers longitudinally about articles in combination with a runway to receive the longitudinally wrapped articles, means for moving the longitudinally wrapped articles through said runway, and means bordering said runway for producing and closing end folds of the wrappers, said latter means including rotatable tucking rolls having means to engage the ends of the wrappers to tuck and fold the same to form closing flaps, means to upturn said closing flaps across the ends of the articles, oscillatable shutters to inwardly down-turn the raised closing flaps over the bodies of the wrappers to complete the wrapping operations. 8. In a machine for the purposes described, means for folding wrappers longitudinally about articles in combination with a runway to receive the longitudinally wrapped articles, means for moving the longitudinally wrapped articles intermittently step by step along said runway, means bordering said runway for producing wrapper end folds, the same comprising rotatable tucking rolls opposed to a point of rest in the travel of longitudinally wrapped articles, said rolls having tucker members, tuck fold turning grooves, and tuck fold creasing and ironing portions, all adapted to provide the wrappers with end closing flaps; means to apply glue to the formed end closing flaps opposed to an advanced point of the travel of longitudinally wrapped articles, the same including yieldable backing means to support the closing flaps subject to operation of the glue applying means; closing flap guiding means intermediate said tucking rolls and glue applying means to lead the closing flaps to and upon said backing means; and means to finally turn the closing flaps across the ends of the articles and into overlying adhering relation to the bodies of the wrappers. 9. In a machine for the purposes described, means for folding wrappers longitudinally about articles in combination with a runway to receive the longitudinally wrapped articles, means for moving the longitudinally wrapped articles intermittently step by step along said runway, means bordering said runway for producing wrapper end folds, the same comprising rotatable tucking rolls opposed to a point of rest in the travel of longitudinally wrapped articles, said rolls having tucker members, tuck fold turning grooves, and tuck fold creasing and ironing portions, all adapted to provide the wrappers with end closing flaps; means to apply glue to the formed end closing flaps opposed to an advanced point of rest in the travel of longitudinally wrapped articles, the same including yieldable backing means to support the closing flaps subject to operation of the glue applying means; closing flap guiding means intermediate said tucking rolls and glue applying means to lead the closing flaps to and upon said backing means; oscillatable shutters, opposed to a further advanced point of rest in the travel of longitudinally wrapped articles to inwardly down-turn closing flaps into overlying adhering relation to the bodies of the wrappers; and means intermediate said glue applying means and said shutters to up-turn the closing flaps across the ends.

of the articles and subject to the operation of said shutters.

10. In a machine for the purposes described, means for folding wrappers longitudinally about articles in combination with a runway to receive the longitudinally wrapped articles, means for moving the longitudinally wrapped articles intermittently step by step along said runway, means bordering said runway for producing wrapper end folds, applying adhesive thereto, and folding the same into final form; the same comprising rotatable tucking rolls opposed to a point of rest in the travel of longitudinally wrapped articles, said rolls having tucker members, tuck fold turning grooves, and tuck fold creasing and ironing portions, all adapted to provide the wrappers with end closing flaps; means to apply glue to the formed end closing flaps opposed to an advanced point of rest in the travel of longitudinally wrapped articles, the same including yieldable backing means to support the closing flaps subject to operation of the glue applying means; closing flap guiding means intermediate said tucking rolls and glue applying means to lead the closing flaps to and upon said backing means; oscillatable shutters, opposed to a further advanced point of rest in the travel of longitudinally wrapped articles, to inwardly down-turn closing flaps into overlying adhering relation to the bodies of the wrappers; means intermediate said glue applying means and said shutters to upturn the closing flaps across the ends of the articles and subject to the operation of said shutters, and spring cushioned shaping members beneath said shutters having curved lips to overhang the ends of the articles and their wrappers, said shaping members being depressible, under downward swinging movement of said shutters, to move their lips into engagement with the wrappers adjacent to the junctures of the closing flaps therewith for the purposes described.

11. In a machine for the purposes described, means for manipulating wrapper end closing flaps comprising oscillatable shutters, spring cushioned shaping members beneath said shutters having curved lips to overhang the ends of articles and their wrappers, said shaping members being depressible, under downward swinging movement of said shutters, to move their lips into engagement with the wrappers adjacent to the junctures of the closing flaps therewith to arch the end of the wrappers about the ends of the articles as the shutters inwardly down-turn said closing flaps over the bodies of the wrappers to complete the wrapping operations.

12. In a machine for the purposes described, an intermittently rotatable carrier head having radial pockets, means for feeding paper from a supply roll across the mouth of a pocket at one side of said carrier

head, reciprocable means for gripping the free end of the fed paper to hold the same smoothly spread while moved and until inserted in said pocket, means for severing the fed paper to form a wrapper, means for moving an article with such wrapper into said carrier head pocket to partially fold the wrapper about the article with a portion thereof projecting from said pocket, means for applying glue to projecting wrapper portions, means to eject partially wrapped articles from said carrier head, a runway to receive the ejected partially wrapped articles, a folder means at the receiving end of said runway adapted to fold the glue bearing portion of a wrapper to complete the longitudinal folding thereof about an article, means for moving longitudinally wrapped articles through said runway, and means bordering said runway for producing and closing end folds of the wrappers, said latter means including rotatable tucking rolls having means to engage the ends of the wrappers to tuck and fold the same to form closing flaps, means to up-turn said closing flaps across the ends of the articles, and oscillatable shutters to inwardly down-turn the raised closing flaps over the bodies of the wrappers to complete the wrapping operations.

13. In a machine for the purposes described, an intermittently rotatable carrier head having radial pockets, means for feeding paper from a supply roll across the mouth of a pocket at one side of said carrier head, reciprocable means for gripping the free end of the fed paper to hold the same smoothly spread while moved and until inserted in said pocket, means for severing the fed paper to form a wrapper, means for moving an article with such wrapper into said carrier head pocket to partially fold the wrapper about the article with a portion thereof projecting from said pocket, means for applying glue to projecting wrapper portions, means to eject partially wrapped articles from said carrier head, a runway to receive the ejected partially wrapped articles, a folder means at the receiving end of said runway adapted to fold the glue bearing portion of a wrapper to complete the longitudinal folding thereof about an article, means for moving longitudinally wrapped articles through said runway, and means bordering said runway for producing and closing end folds of the wrappers, said latter means including rotatable tucking rolls having means to engage the ends of the wrappers to tuck and fold the same to form closing flaps, means to up-turn said closing flaps across the ends of the articles, and oscillatable shutters to inwardly down-turn the raised closing flaps over the bodies of the wrappers to complete the wrapping operations, and means for applying glue to said closing flaps prior to final folding of the same.

pers adjacent to the junctures of the closing flaps therewith for the purposes described.

17. In a machine for the purposes described, a pair of juxtaposed intermittently rotatable carrier heads each having radial pockets, means in timed operative relation to said carrier heads for entering and discharging articles into and out of the pockets thereof while said carrier heads are at rest, means for feeding label bands from a supply thereof across the mouth of a pocket at one side of the first carrier head to be moved with an article thereinto so as to partially fold the same about the article with a portion thereof projecting from said pocket, means intermediate the carrier heads to receive the articles and label bands discharged from said first carrier head and to fold down the projecting ends of the label bands into completed encircling relation to the articles, means for feeding paper from a supply roll across the mouth of a pocket at one side of the second carrier head, reciprocable means for gripping the free end of the fed paper to hold the same smoothly spread while moved and until inserted in said pocket, means for severing the fed paper to form a wrapper movable with the banded article into said pocket to partially fold such wrapper longitudinally about the banded article with a portion thereof projecting from said pocket, a runway to receive the partially wrapped banded articles from said second carrier head, a folder means at the receiving end of said runway adapted to fold down the projecting wrapper portions to complete longitudinal folding thereof about the banded articles, means for moving longitudinally wrapped articles through said runway, and means bordering said runway for producing and closing end folds of the wrappers.

18. In a machine for the purposes described, a pair of juxtaposed intermittently rotatable carrier heads each having radial pockets, means in timed operative relation to said carrier heads for entering and discharging articles therefrom while the same are at rest, means for feeding label bands from a supply thereof across the mouth of a pocket at the forward side of the first carrier head to be moved with an article thereinto so as to partially fold the same about the article with a portion thereof projecting from said pocket, means to apply glue to said label bands, means intermediate the carrier heads to receive the articles and label bands discharged from said first carrier head and to fold down the projecting ends of the label bands into completed encircling relation to the articles, means for feeding paper from a supply roll across the mouth of a pocket at the forward side of the second carrier head, reciprocable means for gripping the free end of the fed paper to hold the same smoothly

spread while moved and until inserted in said pocket, means for severing the fed paper to form a wrapper movable with a banded article into said pocket to partially fold such wrapper longitudinally about the banded article with a portion thereof projecting from said pocket, means for applying glue to the projecting portions of said wrapper, a runway to receive the partially wrapped banded articles from said second carrier head, a folder means at the receiving end of said runway adapted to fold down the projecting wrapper portions to complete longitudinal folding thereof about the banded articles, means for moving longitudinally wrapped articles through said runway, and means bordering said runway for producing and closing end folds of the wrappers.

19. In a machine of the kind described, means for longitudinally folding cellophane paper about articles to be wrapped therein, means for feeding paper from a supply roll into position for delivery to said folding means, means to sever the fed paper to form a wrapper, means for gripping the free end of the fed paper to hold the same smoothly spread until severed and delivered to said folding means, gluing means cooperative with said folding means, a runway through which longitudinally wrapped articles are moved, and means bordering said runway for producing and closing end folds of the wrappers.

20. In a machine of the kind described, means for longitudinally folding cellophane paper about articles to be wrapped therein, means for feeding paper from a supply roll into position for delivery to said folding means, means to sever the fed paper to form a wrapper, means for gripping the free end of the fed paper to hold the same smoothly spread until severed and delivered to said folding means, gluing means cooperative with said folding means, a runway through which longitudinally wrapped articles are moved, and means bordering said runway for producing and closing end folds of the wrapper, said latter means including rotatable tucking rolls having means to engage the ends of the longitudinally folded wrappers to tuck and fold the same to form end closing flaps, means to up-turn said closing flaps across the ends of the articles, and means to inwardly down-turn the raised closing flaps over the bodies of the wrappers to complete the wrapping operations.

21. In a machine of the kind described, means for longitudinally folding cellophane paper about articles to be wrapped therein, means for feeding paper from a supply roll into position for delivery to said folding means, means to sever the fed paper to form a wrapper, means for gripping the free end of the fed paper to hold the same smoothly spread until severed and delivered to said

folding means, gluing means cooperative with said folding means, a runway through which longitudinally wrapped articles are moved, and means bordering said runway
5 for producing and closing end folds of the wrappers, said latter means including rotatable tucking rolls having means to engage the ends of the longitudinally folded wrappers to tuck and fold the same to form end
10 closing flaps, means to up-turn said closing flaps across the ends of the articles, and means to inwardly down-turn the raised closing flaps over the bodies of the wrappers to complete the wrapping operations, and
15 means for applying glue to said closing flaps prior to final folding of the same.

In testimony, that we claim the invention set forth above we have hereunto set our hands this 6th day of February, 1930.

20 HARRY L. EVANS.
